UNITED STATES PATENT OFFICE

ELMER E. NEAL, OF NEW HAVEN, CONNECTICUT, ASSIGNOR TO PEERLESS HANDCUFF CO., OF SPRINGFIELD, MASSACHUSETTS, A CORPORATION OF MASSACHUSETTS

HANDCUFF

Application filed January 12, 1929. Serial No. 332,206.

This invention relates to handcuffs, thumb cuffs, leg cuffs, or similar devices for police use, and has particular reference to a policeman's cuff which will be an improvement, in some particulars to be pointed out, on that described in my prior application for patent Serial No. 321,903 filed Nov. 26, 1928. Specific objects of the present improvement are to give additional security against picking or tampering with the lock mechanism, and to facilitate the withdrawal of the handcuff from the officer's pocket, without catching on the fabric of the pocket or tearing it. Other objects will appear from the following description and claims.

Referring to the drawings:

Fig. 1 is a front view of a handcuff embodying my invention;

Fig. 2 is a side view thereof;

Fig. 3 is a detail, with the front of the lock casing removed, showing the parts in ratcheting position;

Fig. 4 is a similar detail showing the parts in locked position;

Fig. 5 is a similar detail showing the parts in unlocked position;

Fig. 6 is a fragmentary detail similar to Fig. 4 but on a larger scale, illustrating more clearly the construction of certain parts;

Fig. 7 is a perspective detail of a verge or escapement rocker;

Fig. 8 is a perspective detail of the locking pawl;

Fig. 9 is a perspective detail of a bolt; and

Fig. 10 is a detail of a key.

The handcuff is in general outline similar to that shown in my prior application referred to, having a single C-shaped arm 11 formed at one end to receive a pivot pin 12 and shaped at its other end into a lock chamber 13, and a second single arm 14 rotatable on the pivot. The lock chamber is preferably formed integrally with the arm 11, and is closed on all sides except on that which faces the pivot 12. This side is closed by the arm 14 when this arm is in the position shown in the drawing, the arm extending slightly into the lock chamber and being provided with teeth 15. These teeth differ from those shown on the arm in the prior

application in that they are of a symmetrical V-shape instead of being substantially radial on one side. A lip 16 on the lock chamber extends (preferably along the whole length of the lock chamber) into a concentric groove 17 on the arm 14 to prevent tampering with the lock and to add strength to the handcuff.

Pivotedly pinned, at 18 (Fig. 6) within the lock chamber is a straight pawl 19 having a tooth 20 adapted to engage the ratchet teeth 15. A tail 21 extends from the pawl to give support for a spring 22 having a rounded end 23 adapted to seat selectively in recesses 24 or 25 of a bolt 26. This bolt lies freely within the lock chamber, being held down only by the spring 22 and being limited in its reciprocation by shoulders 27 and 28 formed in the chamber. The bolt is adapted to assume three positions, a locked position of

Figs. 4 and 6, an intermediate or ratcheting position shown in Fig. 3, and an unlocking position shown in Fig. 5. In the locked position of the bolt the spring 22 rides in the notch 25 (Fig. 9) and an abutment 29

on the bolt lies under an abutment 30 on the lower side of the pawl (Fig. 6) to prevent rotation of the pawl out of contact with the ratchet teeth. In the ratcheting position the spring 22 lies in the notch 24 and the abutments 29 and 30 are out of contact so that the pawl may click on the ratchet teeth. In the unlocked position the end 31 of the bolt rides under the end 32 of the pawl to rotate the latter to a position completely out of contact with the ratchet teeth, as shown in Fig. 5, the abutment 29 running freely into a central recess 33 in the pawl so that it causes no interference. As in the prior application, the bolt is formed with indentations 34 meshing with teeth 35 on a hollow

key 36 adapted to pass through a key hole 37 in the lock chamber and to rotate upon a pin 38.

The form of teeth shown upon the ratchet-like portion of arm 14 presents certain desirable characteristics from the standpoint of utility. It is possible to set the handcuff as shown in the drawings in this case as well as my former type of handcuff, so that all of the ratchet teeth are enclosed by the lock

chamber, and if the officer is careful to set the handcuff in this position before placing it in his pocket there will be no projections to catch, regardless of the form of ratchet teeth. In practice, however, it is only an unusually careful officer who invariably takes this precaution. In other forms of handcuffs in use the neglect in taking such precaution results in the liability to tear the cloth within the officer's pocket by the sharp teeth of the old form and sometimes in a far more important liability—namely, that of a disastrous delay and confusion in withdrawing the handcuff from the pocket. The symmetrical teeth used in the present case slide freely out of the pocket without the liability of catching or tearing or delaying the officer's movements.

In order to utilize this form of ratchet teeth for the above and other reasons, the locking mechanism has been changed so that the teeth, while symmetrical, will still ride over the pawl only in one direction. This is accomplished by the relative arrangement of the tooth 20 and the pivot 18 of the pawl. Referring to Fig. 6, it will be observed that while if the ratchet be pushed to the right the pawl will click over the teeth, the pressure of the ratchet against teeth when the ratchet is pushed in the opposite direction is in a line passing substantially through the pivot 18 or slightly above it, and no clicking of the pawl will occur. By this special arrangement of the pawl mounting a smooth action of the ratchet in one direction is attained coupled with positive locking in the other direction. Undue swinging of the pawl when the arm 14 is completely out of the lock casing is prevented by contact of the end 32 of the pawl striking a ledge 39 formed on the casing or the adjacent end of bolt 36.

To insure against picking of the lock when set in ratcheting position, a device known (among mechanical movements) as a Swiss verge 40, described and claimed in my prior application Ser. No. 200,466 filed June 21, 1927, is preferably used. This verge is pivoted at 41 within the lock chamber, and is formed with pallets 42 and 43 (Fig. 5) adapted to engage the ratchet teeth 15. This device is preferably set so that one or the other of the pallets, but not both, is always in contact with a ratchet tooth. With this setting the verge oscillates back and forth as the arm 14 is swung into position with the passage of each ratchet tooth. If it be attempted to insert any picking tool such as thin spring into the space between the lock casing and the ratchet at the left as viewed in Fig. 5, the end of the spring cannot pass both ends of the verge, since by its passage past the left-hand end it tilts the right end even more forcefully than usual against the teeth.

Having in mind the desirability of a shallow lock casing which will form a minimum

protuberance from the bracelet form of the cuff, I have added certain features of importance in the lock casing and mechanism not found in prior structures. The bottom wall surface inside the lock casing is curved so as to bring all the mechanism closer to the bracelet curve. The bolt 26 is thin and of the same curve as the bottom wall on which it slides guided by the side walls. The ratchet 19 has a single tooth of sturdy but small bulk, which is enough to lock the toothed arm 14. The ratchet is rocked on its pivot by its flat spring and the movement of the bolt from a position substantially parallel to the bolt to a position just enough off the parallel to lock the toothed arm. This arrangement effectively minimizes the radial distance from the bracelet curve that is needed for the lock mechanism. By providing the space for the key turning in the casing at one side of the latch 19 instead of under or over it and having this space lying in substantially the same annulus from the bracelet curve center as that in which the latch 19 lies, it will be seen how I have deliberately arranged the parts of the locking mechanism and casing so as to hug around the curve of the bracelet with the plan of avoiding an increase in the overall dimensions of the handcuff that is to be carried in the pocket. With such structure the bottom wall of the casing 18 may be curved so as to form substantially a stream line with the bracelet circumference as a whole and of substantially the same radius.

It will be noted in the form of handcuff shown that the walls of the lock casing may all be integral, including the end walls. By reason of the verge device the clearance between the ratchet teeth and the top of the end wall of the casing, which in constructions formerly used, needed to be as small as possible to prevent the insertion of a picking tool, can now be made within greater tolerances, and to take full advantage of this fact I have made the end walls integral. The verge is thus important in not only actually preventing lock picking by its positive action, but in making possible more economical manufacture. It is a fact that in handcuff manufacture a very large expense has been customary in the work of insuring accurate assembly, fitting, and adjustment of the parts such as required by the clearance referred to. The verge structure, in combination with the form of lock mechanism and casing walls shown, improves the handcuff function and cuts down the amount of skill required in providing a good structure.

The invention is described in the form of a handcuff with the understanding that the term "handcuff" or "policeman's cuff" includes all analogous articles like thumb cuffs, leg irons, neck rings, and such devices for locking prisoners.

What I claim is:

1. A policeman's cuff comprising a curved arm terminating in a lock casing, a second curved arm pivoted to the first arm and having substantially symmetrical ratchet teeth on its periphery, a pawl pivoted intermediate its length in the lock casing with its pivot point substantially in the line of the thrust exerted upon the pawl by the ratchet as the second arm is moved in one direction, means for pressing the pawl yieldably against the ratchet teeth to permit clicking of the pawl when the second arm is moved in the reverse direction, means for engaging the pawl on one side of its pivot point for holding it immovable against the ratchet teeth and thereby locking the second arm against movement in either direction, and means for engaging the pawl on the other side of its pivot point for withdrawing it from contact with the ratchet teeth. 70
2. A policeman's cuff comprising a curved arm terminating in a lock casing, a second curved arm pivoted to the first and having substantially symmetrical ratchet teeth on its periphery, a pawl pivoted in the lock casing at such an angle that the line of thrust exerted on it by the ratchet teeth in one direction passes substantially through its pivot, thus preventing movement of the ratchet in that direction, whereas the pawl will click idly over the ratchet teeth during movement of the ratchet in the other direction, a sliding bolt within the lock casing adapted in one position to hold the pawl immovably against the ratchet teeth and in another position to tilt the pawl out of contact with the ratchet teeth, a spring secured to the pawl tending to press the pawl towards the ratchet teeth, the free end of the spring riding on the bolt, and recesses in the bolt into which the free end of the spring may drop to hold the pawl selectively and releasably in one of a plurality of positions. 85
3. A policeman's cuff comprising a curved arm terminating in a lock casing, a second curved arm pivoted to the first and having substantially symmetrical ratchet teeth on its periphery, a pawl pivoted in the lock casing at such an angle that the line of thrust exerted on it by the ratchet teeth in one direction passes substantially through its pivot, thus preventing movement of the ratchet in that direction, whereas the pawl will click idly over the ratchet teeth during movement of the ratchet in the other direction, a sliding bolt within the lock casing adapted in one position to hold the pawl immovably against the ratchet teeth and in another position to tilt the pawl out of contact with the ratchet teeth, and a spring urging the pawl into contact with the ratchet. 95
4. A policeman's cuff comprising a curved arm terminating in a lock casing the outer wall of which is of substantially the same

curvature and from the same center as the arm, a second curved arm pivoted to the first and having substantially symmetrical ratchet teeth on a portion of its periphery, a pawl mounted in the lock casing permitting clicking of the ratchet in one direction but preventing its movement in the other direction, and key operable bolt means movable to a position for holding the pawl out of position for engaging said teeth and to another position for holding the pawl in such engagement. 105

5. A policeman's cuff comprising a curved arm terminating in a lock casing the inner bottom wall of which is on substantially the same curvature and from the same center as the arm, a long thin curved bolt lying on said wall and extending between the side walls of the casing, a straight ratchet pivoted in the casing above the bolt, a flat spring between the bolt and one end of the ratchet, key engaging means on the bolt at one side of the ratchet, means on the bolt to tip the ratchet against the action of the spring and a verge in the lock casing at the side of the ratchet opposite to the key engaging means and a second curved arm pivoted to the first arm with ratchet teeth adapted to operate said verge and be locked by said ratchet when positioned by the bolt. 90

In testimony whereof I have affixed my signature.
